UNITED STATES PATENT OFFICE.

JAMES L. JOHNSTON, OF TOPEKA, KANSAS.

VEHICLE-HUB.

SPECIFICATION forming part of Letters Patent No. 349,433, dated September 21, 1886.

Application filed July 3, 1886. Serial No. 207,093. (No model.)

To all whom it may concern:

Be it known that I, JAMES L. JOHNSTON, a citizen of the United States, residing at Topeka, in the county of Shawnee and State of Kansas, have invented new and useful Improvements in Vehicle-Hub Rings and Spoke-Sockets, of which the following is a specification.

This invention relates to certain new and useful improvements in hubs and spoke-sockets for vehicle-wheels; and it consists, substantially, in the same as constructed, and in such other details and combinations of parts as will hereinafter be distinctly described, and 15 pointed out in the claims.

The general objects of the invention will appear from the description hereinafter following; and in carrying out the invention I employ an axle-box and hub-rings of such peculiarities of construction as that the latter are held or maintained positively against axial movement with respect to the former, a maximum degree of strength attained from a minimum amount of material, and a consequent decrease in the weight of the parts; and, further, the spoke-sockets are so formed as to facilitate a much easier and more rapid insertion of the inner ends of the spokes than has heretofore been accomplished by inventions 25 of a like character.

Referring to the accompanying drawings, Figure 1 represents a longitudinal sectional view of axle-box and hub-rings constructed in accordance with my invention. Fig. 2 represents an inner plan or face view of one of the hub-rings; and Fig. 3 represents a sectional view of the box and ring, taken on the line $x-x$ of Fig. 1. Fig. 4 represents a modification.

Reference being had to the several parts by 40 the letters marked thereon, A denotes an axle-box constructed in accordance with my invention, the same being formed screw-threaded at one end and enlarged at the other, as shown.

Formed with and surrounding the said box 45 adjacent to its enlarged end is a collar or circumferential flange, a , while at a point of said flange a projection or lug, b , is provided. This lug tapers inwardly at the sides in the form of a wedge, as shown, and is designed to enter a 50 correspondingly-shaped recess on the inner side of the hub-ring, by which the box is pre-

vented from movement when properly placed within the latter.

B B represent the hub-rings, which are counterparts in construction, the same being 55 formed with radial sockets c for the reception of the inner ends of the spokes, the said sockets of each ring tending or inclining slightly toward those of its fellow, as shown, in order that the spokes will be given the 60 proper "dish" or relativity. These rings are placed with the sockets c of one alternating in position with the sockets of the other, this being usual in the present class of vehicle-wheels. The inner sides of the rings are made 65 at right angles, and they are supported and connected interiorly by radial webs or partitions d , each one of which, if continued across the ring, would pass through its center, thus providing wedge-shaped recesses e between them, 70 into which the wedge-shaped lug b on the axle-box is received when properly placed into the hub-rings. By this construction of hub-ring it will be seen that a great saving of material is effected, together with a reduction in weight 75 of the several parts, while at the same time the greatest amount of strength is obtained. The webs d , concentrating toward the center of the rings, bear upon the perimeter of the axle-box, thus equalizing the strain imposed 80 on the rings. The end and edge of each web or partition are grooved, as shown at f , for the purpose of receiving the projection formed by the manner of fitting up the box, thereby allowing the edge of the ring to fit snugly 85 against the collar a when the box is inserted. It will be apparent that in consequence of the spaces e no difficulty will be experienced in adjusting or replacing the box into the rings, since all that is required is to simply force the 90 box in with little or no turning thereof. It will be seen that the webs d are so disposed as to be brought beneath the sockets c , (this being preferred, although I do not confine myself to this precise location,) by which it is 95 evident that additional strength is afforded the same and an increased resistance supplied against the force necessary to insert the spokes, and also prevents the box from working loose in the rings.

i represents an opening or vent that is formed either at the base of the sockets, as

shown in Fig. 3, or the same may be formed in the side thereof, as indicated in Fig. 4. In the present class of inventions it has formerly been quite difficult to insert the spokes into their sockets as tightly as is requisite, for the reason that a certain amount of air is always contained in the latter, which becomes compressed in the bottom of the sockets and does not allow the spokes to be driven entirely to the bottom. By the employment of these openings the air contained in the sockets is forced out on the insertion of the spokes, and thus is the difficulty which has heretofore been attendant on this operation greatly lessened. 15 Heretofore it has been found necessary to at first insert the spokes into their sockets and drive them down or in as far as possible, and then wait until the contained air has escaped or become absorbed, and again subject the 20 spokes to a further force to insure their tightness of fit; but with my construction this is entirely obviated, and the spokes may be inserted and driven very tightly into place at one operation. It will be seen that the ring 25 which is engaged and held by the projecting lug of the box will, by virtue of the spoke and rim connection usually made, also prevent movement of the other ring, and the prime feature of constructing the two rings alike is that the 30 parts will be of equal symmetry and weight, and that the box can be inserted in the wheel irrespective of the side at which it is introduced.

C represents a rubber cushion or ring which 35 is placed between the rings before the box is inserted, the same being of ordinary form; and D designates a nut for forcing the hub-rings together to compensate for looseness of the spokes.

40 From the foregoing description it will be

seen that a wheel embodying the features herein named can be constructed at a much less cost than those heretofore employed for the same purpose, and its simplicity and other valuable characteristics will be equally manifest. 45

Having thus described my invention, what I claim as new, and desire to secure by Letters Patent, is—

1. A hub-ring for vehicles, provided with 50 radial spoke-sockets and having the webs or ribs d, notched or recessed at their ends, substantially as described.

2. A hub-ring for vehicles, provided with 55 radial spoke-sockets having each an opening or vent, and formed with the webs d, having notched or recessed ends, substantially as described.

3. A hub for vehicles, consisting of two 60 rings, each of which is provided with radial spoke-sockets and recessed on their inner sides, the said recesses being formed in the webs d, as and in the manner described.

4. The combination, with the axle-box having the wedge-shaped lug b, of the rings B B, 65 having the webs d and intermediate spaces for the reception of the lug, substantially as described.

5. The combination, with the axle-box having the flange a and lug b, of the rings B B, 70 having the webs d, recessed at their ends, substantially as and for the purpose described.

In testimony whereof I have hereunto set my hand in the presence of two subscribing witnesses.

JAMES L. JOHNSTON.
